RECEPTACLE FOR A ROLL OF TOILET TISSUE

Elmer H. Davis, 1000 Urlin Ave.,
Columbus, Ohio 43212

Filed Dec. 5, 1967, Ser. No. 9,638

Term of patent 14 years

Int. Cl. D6—01

U.S. Cl. D33—31

FIG. 1 is a perspective view of a receptacle for a roll of toilet tissue showing my new design; and

FIG. 2 is a medial vertical cross-sectional view thereof.

The broken line representation of a roll of toilet tissue in FIGS. 1 and 2 is for purposes of illustration only.

I claim:

The ornamental design for a receptacle for a roll of toilet tissue, substantially as shown and described.
